(57) **CLAIM**

The ornamental design for a smoking article filter, as shown and described.

DESCRIPTION

FIG. 1 is a front view of a first embodiment of a smoking article filter, embodying our new design;

FIG. 2 is a rear view thereof;

FIG. 3 is a side view thereof;

FIG. 4 is a front and side perspective view thereof;

FIG. 5 is a front view of a second embodiment of a smoking article filter, embodying our new design;

FIG. 6 is a rear view thereof;

FIG. 7 is a side view thereof;

FIG. 8 is a front and side perspective view thereof;

FIG. 9 is a front view of a third embodiment of a smoking article filter, embodying our new design;

FIG. 10 is a rear view thereof;

FIG. 11 is a side view thereof;

FIG. 12 is a front and side perspective view thereof;

FIG. 13 is a front view of a fourth embodiment of a smoking article filter, embodying our new design;

FIG. 14 is a rear view thereof;

FIG. 15 is a side view thereof;

FIG. 16 is a front and side perspective view thereof;

FIG. 17 is a front view of a fifth embodiment of a smoking article filter, embodying our new design;

FIG. 18 is a rear view thereof;

FIG. 19 is a side view thereof; and,

FIG. 20 is a front and side perspective view thereof.

The broken lines showing various features on the smoking article filter are for illustration purposes only and form no part of the claimed design.
